UNITED STATES PATENT OFFICE.

JAMES JOHNSTON, OF JAMAICA PLAIN, MASSACHUSETTS.

ARTIFICIAL LEG.

SPECIFICATION forming part of Letters Patent No. 746,336, dated December 8, 1903.

Application filed July 23, 1903. Serial No. 166,664. (No model.)

To all whom it may concern:

Be it known that I, JAMES JOHNSTON, a subject of the King of England, residing at Jamaica Plain, in the county of Suffolk and State of Massachusetts, have invented new and useful Improvements in Artificial Legs, of which the following is a specification.

- This invention relates to an improvement in artificial legs, the object of the invention being to provide means for compensating for the wear or stretching of the elastic bands which connect one leg-section to a slip-socket, and thus make sure that there is no play between the socket and the stump of the leg.
- 15 The invention consists, mainly, in an adjustable plate consisting of two pieces, one fast to the socket, the other fastened to an elastic band, which in turn is fastened to a leg-section, the two parts of said plate being adjustable with relation to each other, so that the length of the plate may be increased or diminished, as may be desired.

20 The invention further consists in the combination and arrangement of parts set forth in the following specification and particularly pointed out in the claims thereof.

25 Referring to the drawings, Figure 1 is a perspective view of an artificial leg constructed in accordance with my invention.

30 Fig. 2 is an enlarged side elevation of a portion of the lower leg-section. Fig. 3 is a section, partly in elevation, taken on line 3 3 of Fig. 2. Fig. 4 is a transverse section taken on line 4 4 of Fig. 2, the rivets being shown 35 in elevation. Fig. 5 is a detail rear elevation of the extensible plate.

Like numerals refer to like parts throughout the several views of the drawings.

30 In the drawings, 6 is an upper leg-section, and 7 a lower leg-section. The upper leg-section 6 is provided with side braces 8 8, pivoted at 9 to side braces 10 10, fast to the lower leg-section 7. The side braces 10 10 are each provided with a slot 11 and have fastened thereto at the upper end of said slot an elastic band 12. The lower end of the elastic band 12 is fastened by rivets 13 to the upper end of the extensible plate 14. The lower end of said plate 14 is fastened by rivets 16 to 45 a slip-socket 15, which is adapted to be laced to the leg-stump. The leg-sections 6 and 7 and

the slip-socket 15 are all old and well known to those skilled in this art; but the manner in which the elastic band 12 is connected to the slip-socket by means of an extensible plate 14 55 constitutes the novel portion of my invention. The plate 14 is made in two parts, an upper part 17 and a lower part 18, joined together by a clamp-plate 19. The clamp-plate 19 is rigidly fastened to the lower part 18 by 60 a screw 20, which may have screw-threaded engagement with any one of the holes 21 21 21, provided in the lower part 18. The upper end of the clamp-plate 19 is constructed with a tongue 22, which projects through a slot 23, 65 provided in the upper part 17, and which also projects through one of the slots 24 24 24, provided in the lower part 18. It will be seen that by screwing the clamp-plate to the lower plate 18, with the tongue 22 projecting through 70 the slots 23 and 24, the two parts 17 and 18 will be joined together in a very rigid and strong manner and that by changing the screw 20 to different holes 21 and the tongue 22 to project through different slots 24 the 75 length of the plate or the distance between the extreme ends of the upper and lower parts of said plate may be varied to compensate for wear or stretching of the elastic band 12.

It is evident that the elastic band 12 and 80 the extensible plate 14 form when joined together an extensible elastic connection one end of which is connected to a leg-section and the other to a slip-socket.

85 While the drawings disclose an extensible plate and elastic band forming an extensible elastic connection on one side only of the artificial leg, it will be understood that the elastic band and extensible plate are used in duplicate, one upon each side of the leg. 90

Having thus described my invention, what I claim, and desire by Letters Patent to secure, is—

1. An artificial leg comprising in its construction a leg-section, a slip-socket, and an adjustable elastic connection, consisting of an elastic band and an extensible plate, said band and plate fast, one to the leg and the other to the socket. 95

2. An artificial leg comprising in its construction a leg-section, a slip-socket, an elastic band fast to said leg-section, an extensi- 100

ble plate made in two parts, one of said parts fast to said elastic band, the other to said slip-socket, and a clamp-plate connecting said parts together, said clamp-plate fast to
5 one of said parts and having a tongue constructed to project through a slot in each of the other of said parts.

In testimony whereof I have hereunto set my hand in presence of two subscribing witnesses.

JAMES JOHNSTON.
